UNITED STATES PATENT OFFICE.

DANIEL J. DAVIS, OF CHICAGO, ILLINOIS, ASSIGNOR OF ONE-THIRD TO STEPHEN J. DAVIS
AND ONE-THIRD TO ALBERT J. DAVIS, BOTH OF CHICAGO, ILLINOIS.

BOTTLE-FILLING APPARATUS.

No. 879,138.

Specification of Letters Patent.

Patented Feb. 11, 1908.

Application filed May 15, 1905. Serial No. 260,452.

To all whom it may concern:

Be it known that DANIEL J. DAVIS, citizen of the United States, residing at Chicago, in the county of Cook and State of Illinois, 5 has invented new and useful Improvements in Bottle-Filling Apparatus, of which the following is a specification.

This invention relates to improvements in a bottle filling apparatus for general purposes, but is more especially intended for the use of dairymen and dealers in filling milk and cream-bottles; and has for its object to provide an apparatus of this character whereby the operation may be accomplished with 15 facility and in accordance with sanitary conditions and requirements.

The apparatus will ordinarily be made up of a number of individual filling devices arranged in series in accordance with the capacity required in filling a number of bottles or vessels simultaneously. It will be understood however, that the apparatus may consist of one, two, three or more individual fillers, and from that number up to any desired 25 practical limit.

The operation of an apparatus comprising a series of fillers, is such, that one or more bottles may be filled at a time, as each individual filler has an independent action governed by the number of bottles placed in position to be filled.

In the drawing, Figure 1 is an elevation of an apparatus arranged in series. Fig. 2 is a vertical section of one of the individual filling devices, a bottle being shown in position which corresponds to the relative position of the series shown in Fig. 1; and Fig. 3 is a vertical section showing the different parts in their opposite or abnormal position from that 40 shown in Fig. 2.

A may represent a receptacle or reservoir suitably supported in position and which contains the milk or other liquid product to be run into the bottles.

45 A socket-piece B is rigidly secured to the receptacle A, one for each individual filling device when arranged in series. The upper end of a combined filling-tube and valve stem C has a screw threaded engagement with the socket-piece as at b, Fig. 2. A vertically slidable sleeve D is telescoped on the filling-tube C and is provided with a shoulder 50 4 for a bearing support of the lower end of a spring 5 encircling the socket B and the sleeve D. The upper end of this spring bears

against a flange 6 forming a part of the socket-piece. The upper portion of the sleeve D closely conforms to the filling-tube, the lower part being of a greater diameter and provides for an annular space 7 therebetween 60 into which the liquid flows from the filling-tube through port or slot openings 8 on its passage to the outlet or discharge end as indicated by the arrows in Fig. 3.

It will be noted that the lower end of the 65 sleeve D is disposed a suitable distance beneath the openings 8; and, as will be readily seen, by glancing at the arrows in Fig. 3, the advantage of these openings 8, in connection with the disposition relative thereto of the 70 lower end of the sleeve D, is that the fall of the liquid through the filling-tube C is broken at the point of said openings, and is caused to flow in a sheet against and down the interior walls of the sleeve D, thence onto the beveled 75 surface 11, and thence down the interior walls of the bottle, all as graphically illustrated by the arrows in Fig. 3.

It will be understood that the description 80 of one individual filling device will answer for the series, the same reference characters being applied to duplicate parts.

A disk-valve 9 is mounted on the lower end of the stationary filling-tube C. The lower end of the movable sleeve D is provided with 85 a beveled valve-seat 10, and the annular valve 9 with a correspondingly beveled surface 11, adapted to come together in the closed position shown in Fig. 2. The opposite or open position being shown in Fig. 3. 90 It will be understood by this arrangement that the valve 9 occupies a stationary position, the valve-seat 10 being movable away from and towards the valve in opening and closing the fluid passage coincident with that 95 of the vertical movement of the sleeve D. The lower end of the filling-tube is provided with a chamber 12, just above the shut-off valve 9, in which is loosely placed a ball-valve 13, normally seating downward and 100 closing the air escape opening 14 through the valve 9. The wire guards 15 prevent the ball-valve from back seating and closing the passage leading out through the air-tube 16. Said air tube is threaded at its lower 105 end, at 27, into the bore of the filling tube below the openings 8, thus closing the lower end of the filling tube to the passage of liquid. The tube 16 may be readily removed to facilitate cleaning.

A conical flaring cap 17 is threaded on the lower end of sleeve D and may be moved upward or downward thereon in properly adjusting the position of the same with reference to the height of the bottle and the relative position of the valve 9 in the neck in filling the bottle to a certain level. The chamber 18 in the conical cap provides for the insertion of a cushioning air-tight gasket 19. 10 This gasket is provided with a rim or lip edge 20 which extends over and has a close fitting bearing with the exterior neck of the bottle 21 when contacting the same in the operation of filling.

15 The bottles to be filled are arranged on an endwise movable tray 22, which is in turn supported on a vertically movable table or platform 23 which may be raised upward at the proper time by means of a foot-treadle 20 and connections 24, as shown in Fig. 1. The bottles to be filled are placed on the tray 22, one under each individual filling-tube; the relative normal position of the bottles and filling mechanism being clearly indicated in 25 Figs. 1 and 2. The lowermost position of the valve 9 in the neck of the bottle will be just below the shoulder 25 on which the paper closing cap seats. This is to permit of a bottle being filled close up to a level with the 30 shoulder 25 at one operation, so as to leave no air space between the cap and surface of the milk. The annular air-space 26 between the flexible gasket 19 and the shoulder 25 on the interior neck of the bottle will ordinarily prevent the milk from coming in contact with the gasket, which will usually be composed of rubber or other suitable elastic substance.

35 The valve 9 is of a less diameter than the 40 surrounding wall of the bottle and provides an annular space for the downward flow of the milk. This valve also has the functions of a spreader and distributes the incoming volume of milk equally against the interior 45 sides of the bottle in a thin sheet and causes the same to follow the sides down to the bottom as indicated by the arrows. The milk or other fluid entering and following down the sides of the bottle does not boil up or 50 foam as it would if the milk flowed down the center of the bottle and struck the bottom with more or less force and mixing with the air. A body of foam forming on top of the milk prevents the bottle being filled to the 55 desired level at the one operation. The milk flowing down the sides of the bottle leaves the center space clear so that the air is gradually displaced and forced upward as indicated by the arrows, and expelled through 60 the air-tube into the atmosphere.

In practical working the bottles are raised upward and coming in contact with the cushioning gaskets forces the sleeve inclosing the milk tube upward against the pressure of 65 its spring and at the same time moves the

valve seat away from the valve and opens the milk passage which allows the milk to flow into and fill the bottles. When the bottles are lowered and the pressure relaxed the sleeve carrying the valve-seat is returned to its normal position, the seat engaging the valve and shutting off the flow. With a very little experience the operator will be able to shut off the flow instantly at the right moment and fill the bottles flush with the 75 shoulder on which the closing caps rest.

Having thus described my invention, what I claim is:

1. In a bottle-filling apparatus, a filling-tube adapted to be connected with a source 80 of supply and having lateral openings through its lower portion, the tube being closed below said openings, a valve secured rigidly to said tube below said openings, a sleeve inclosing and having a vertical movement 85 relative to said tube, being spaced laterally therefrom in the region of and beneath said openings, there being thus formed an annular discharge-chamber between the tube and sleeve, and the lower end of the sleeve being 90 disposed a suitable distance beneath said openings and constituted as a seat for closing against said valve, and in air-tube adapted to permit escape of air within the bottle.

2. In a bottle-filling apparatus, a filling-tube adapted to be connected with a source 95 of supply and having lateral openings through its lower portion, an air-tube secured within said filling-tube and closing the same below said openings, an outward-projecting valve 100 secured to the filling-tube below said openings, and a sleeve inclosing and having a vertical movement relative to said filling-tube, being spaced laterally therefrom in the region of said openings, there being thus 105 formed an annular discharge-chamber between the filling-tube and sleeve, and the lower end of the sleeve being disposed a suitable distance beneath said openings and constituted as a seat for closing against said 110 valve.

3. In a bottle-filling apparatus, a filling-tube adapted to be connected with a source 115 of supply, and having lateral openings through its lower portion, the tube being closed below said openings, a valve secured rigidly to said tube below said openings, a sleeve inclosing said tube, being slidably fitted on the upper portion thereof and of enlarged bore at its lower portion, thus forming an annular discharge chamber between the tube and sleeve in the region of said openings, and the lower end of the sleeve being disposed a suitable distance beneath said 120 openings and constituted as a seat for closing against said valve, and an air-tube adapted to permit escape of air within the bottle.

4. In a bottle-filling apparatus, a filling-tube adapted to be removably connected with a source of supply and having lateral 130

openings through its lower portion, an air-tube within the filling-tube, having its lower end screwed into the interior thereof below said openings, an outward-projecting valve secured to said filling-tube below said openings, and a sleeve inclosing and having a vertical movement relative to said filling-tube, being spaced laterally therefrom in the region of said openings, there being thus 10 formed an annular discharge-chamber between the filling-tube and sleeve, and the

lower end of the sleeve being disposed a suitable distance beneath said openings and constituted as a seat for closing against said valve. 15

In testimony whereof I affix my signature, in presence of two subscribing witnesses.

DANIEL J. DAVIS.
